UNITED STATES PATENT OFFICE.

MONROE S. CLAWSON, OF MONTCLAIR, NEW JERSEY.

TROUSERS HANGER.

Application filed May 23, 1925. Serial No. 32,428.

This invention relates to supports, particularly garment hangers, and has for its object the provision of a novel device capable of being mounted upon the wall of a closet, 5 wardrobe or the like, or in fact at any other desired and suitable location and adapted to hold a plurality of pairs of trousers, all being suspended and held in taut condition whereby they will be properly retained in 10 shape and prevented from becoming wrinkled or losing their crease.

An important object of the invention is to provide a garment support of this character which is extensible and consequently 15 suitable for holding a large number of pairs of trousers in a very compact form or arrangement.

Another object is to provide a trousers hanger which is designed to engage the belt 20 straps for effecting suspension, the strap engaging means being, moreover, adjustable whereby the device will be capable of holding, tautly and firmly, trousers of any size.

Another important feature is the provision 25 of a support of this character so constructed and arranged that all the trousers in advance of the particular pair to be removed may be lifted away at one time so that access 30 may be had to the desired pair without necessitating removal of each pair individually to reach the one wanted.

A more specific object of the invention is to provide a device of this character embodying relatively stationary and movable 35 supporting elements having telescopic engagement, the outer member having its terminal portion of such formation as to prevent catching of the belt straps of the trousers, the terminal portion being cut at an 40 angle and beveled so that when the trousers are moved along the supporting members the straps will ride freely up the inclined ends.

An additional object is the provision of 45 a device of this character which will be simple and inexpensive in manufacture, easy to use, positive in action, efficient, convenient and durable in service, and a general improvement in the art.

To the attainment of the foregoing and 50 other objects and advantages the invention preferably consists in the details of construction and the arrangement and combination of parts to be hereinafter more fully described and claimed, and illustrated in the 55 accompanying drawings in which:

Figure 1 is a perspective view of the device showing it supporting several pairs of trousers,

Figure 2 is a plan view of the device 60 alone, the parts or sections thereof being shown separated and portions being broken away and in section,

Figure 3 is a detail vertical cross section taken on the line 3-3 of Figure 2, and

Figure 4 is a detail perspective view showing the formation of the ends of the outer telescopic members.

Referring more particularly to the drawings I have shown the device as comprising members designated generally by the numerals 10 and 11. While either of these members may be considered as the stationary one, I have, for the sake of illustration, shown the member 10 as intended to be stationary. In actual practice this member may consist 70 of or comprise an elongated attaching plate 12 suitably apertured for the passage of securing screws 13 whereby the device may be fastened to the wall or door of a closet, wardrobe or the like. It is of course conceivable 80 that the device might be mounted within a trunk or at any other desired location though illustration and mention of all possibilities is obviously unnecessary. The intermediate portion of the plate 12 is preferably 85 outwardly pressed or offset as indicated at 14 and near its ends this portion is formed with a plurality of holes 15 within selected ones of which may be passed the reduced threaded ends 16 of rods 17 which extend forwardly from the plate 12 in spaced parallel relation and horizontal position. The extensions 16 carry nuts 18 for effecting securing, these nuts being accommodated within the space formed by offsetting the intermediate portion of the plate. It is preferable 90 that the rods have enlargements 19 thereon contacting with the forward or outer face of the offset portion 14 in order that the rods will be held rigidly and be prevented from sagging or becoming loosened.

The provision of the plurality of holes 15 is important as it permits the rods 17 to be located any desired distance apart depending upon the size of the waist bands of the 105 trousers to be suspended.

The member 11 likewise consists of an elongated plate 20 provided near its ends with a plurality of holes 21. This plate carries a pair of tubular members 22 adapted 110

to telescope onto the rods 17. Near their ends the members 22 are pressed or otherwise formed to provide enlargements 23 outwardly of which the ends are threaded so as 5 to be engaged within selected ones of the holes 21 and to carry securing nuts 24. Obviously the spacing of the holes 21 must be the same as the spacing of the holes 15 as the tubular members 22 must be the same 10 distance apart as the rods 17 so as to be capable of engagement thereon. The enlargements 23 bear against the inner face of the plate 20 and will cooperate with the nuts 24 for guiding the tubular members 15 22 rigid with respect to the plate 20 so that any looseness or distortion will be prevented even after prolonged service.

The rods 17 and tubular members 22 are intended, separately and when assembled, 20 to support a plurality of pairs of trousers indicated at A and B, the forwardmost and rearmost belt straps C thereof being engaged upon the tubes and rods as clearly indicated in Figure 1.

25 In the operation, to be described, it is necessary that the trousers or the straps thereof must be slid along the rods and tubes. For this reason it is necessary that the construction be such that the strips will 30 not hang or catch on the ends of the tubular members. To avoid this the tubular members have their free ends cut away at an angle or inclined as clearly indicated, the heel 25 of the angle being at the upper and 35 outer portion of each tubular member and the toe 26 being at the lower and inner side. Furthermore the ends are beveled as shown at 27 so as to avoid the formation of a shoulder.

40 In the use of the device it will be seen that a large number of pairs of trousers may be supported and suspended in close compact relation as illustrated in Figure 1, it being immaterial whether the straps be 45 engaged upon the rods or the tubular members or both. Naturally, it is intended that if the number of pairs supported be sufficiently small, the sections 10 and 11 may be pushed together as far as possible so as 50 to make the size of the hanger with the garments thereon as small as possible. Whenever it is desired to remove a certain pair, for instance the one indicated at B in Figure 1 all those in advance of this pair are 55 slid forwardly or toward the plate 20, the straps C thereof passing onto the tubular members 22. The entire section 11 carrying these trousers is then removed by the simple process of sliding it away from the 60 section 10. The trousers B may then be slid off from the rods 17, subsequently to which the tubular members 22 are re-engaged upon the rods 17 and the section 11 slid toward the section 10. In this way it 65 is quite evident that it is unnecessary to re-

move the successive pairs of trousers individually to gain access to the desired pair. Owing to the peculiar construction of the free ends of the tubular members 22 it will be seen that when the tubular members 70 are slid through the belt straps of trousers suspended from the rods 17, or when the belt straps are slid from the rods 17 onto the tubular members 23 there will be nothing to catch, the straps riding freely and 75 easily along the inclined or angular and beveled ends of the tubular members. Furthermore, as the angles are such that the heels are disposed upwardly and outwardly it is evident that there is a tendency to 80 force the belt straps outwardly, thus placing the waist bands of the trousers under tension so that the garments will be held taut and prevented from sagging or drooping. Quite naturally the garments will be 85 retained in their proper condition and wrinkling or loss of crease prevented.

As an additional convenience the plate 20 may be provided with hooks 28 and 29 on which may be hung the trousers in daily 90 use. The hook 28 is shown as secured upon the intermediate portion of the plate 20 by any desired means while the hooks 29 may be formed integrally upon the nuts 24.

From the foregoing description and a 95 study of the drawings it will be seen that I have thus provided a simply constructed, neat, attractive, convenient and also highly efficient device for the purpose described which will take care of a large number of garments in a very satisfactory manner and maintain them in proper condition as well as keeping them arranged in a compact form so as to occupy the minimum storage space.

While I have shown and described a preferred embodiment of the invention, it should be understood that I reserve the right to make all such changes in the details of construction and the form and arrangement of parts as will not depart from the spirit of the invention or the scope of the subjoined claims.

Having thus described the invention, I claim:

1. A garment hanger comprising a relatively stationary member including a plurality of spaced horizontally extending supporting elements, and a second member including horizontal supporting elements telescopically engaged with the first named supporting elements, all of said supporting elements being adapted for insertion through the belt straps at the front and rear of trousers for effecting suspension thereof and maintaining them taut at the waists thereof.

2. A garment hanger comprising a relatively stationary member including spaced parallel horizontally extending supporting elements, and a second member including

- supporting elements telescopically engaged with the first named supporting elements, all of said supporting elements being adapted for insertion through the belt straps at the front and rear of trousers for effecting suspension thereof, and means for adjusting the first and second named elements laterally for accommodating trousers having different waist measure.
5. A garment hanger comprising a stationary section including an attaching plate and a pair of horizontally disposed spaced parallel rods carried thereby, and a relatively movable member including a plate carrying a pair of spaced parallel horizontally disposed tubular members telescopically engageable upon said rods, said rods and tubular members being disposable through the belt straps at the front and rear of trousers for effecting suspension thereof.
10. 3. A garment hanger comprising a stationary section including an attaching plate and a pair of horizontally disposed spaced parallel rods carried thereby, and a relatively movable member including a plate carrying a pair of spaced parallel horizontally disposed tubular members telescopically engageable upon said rods, said rods and tubular members being disposable through the belt straps at the front and rear of trousers for effecting suspension thereof.
15. 4. A garment hanger comprising a stationary section including an attached plate and a pair of horizontally disposed spaced parallel rods carried thereby, and a relatively movable member including a plate carrying a pair of spaced parallel horizontally disposed tubular members telescopically engageable upon said rods, said rods and tubular members being disposable through the belt straps at the front and rear of trousers for effecting suspension thereof, the free ends of the tubular members being inclined with the heel of the angle located upwardly and outwardly and with the toe located inwardly and downwardly.
20. 5. A garment hanger comprising a relatively stationary member including a plurality of spaced substantially horizontally extending supporting elements, and a second movable member including substantially horizontal supporting elements slidably engaged with the first named supporting elements, all of said supporting elements being adapted for insertion through the belt straps at the front and rear of trousers for effecting suspension thereof and maintaining them taut at the waists thereof.
25. 6. A device of the character described comprising a relatively stationary section including an attaching plate having its intermediate portion forwardly offset and formed with groups of holes, a pair of rods having threaded ends extending through selected ones of said holes and equipped with nuts located within said forwardly offset portions, and a relatively movable member including a plate provided with groups of holes, tubular members having threaded extensions engaged through selected ones of the second named holes and carrying nuts, the tubular members being telescopically engageable upon said rods.
30. 7. A device of the character described comprising a relatively stationary section including an attaching plate having its intermediate portion forwardly offset and formed with groups of holes, a pair of rods having threaded ends extending through selected ones of said holes and equipped with nuts located within said forwardly offset portions, and a relatively movable member including a plate provided with groups of holes, tubular members having threaded extensions engaged through selected ones of the holes and carrying nuts, the tubular members being telescopically engageable upon said rods.
35. 8. A device of the character described comprising a relatively stationary member and a relatively moveable member, telescopic elements adjustably and detachably connected with said members and adapted for insertion through the belt straps at the front and rear of pairs of trousers, and means for adjusting the telescopic elements laterally with respect to each other.
40. 9. A device of the character described comprising a relatively stationary member and a relatively movable member, telescopic elements adjustably and detachably connected with said members and adapted for insertion through the belt straps at the front and rear of pairs of trousers, the outer telescopic members having their free ends cut away at an angle inclining upwardly and outwardly whereby to provide inclined surfaces engageable by the belt straps for urging the same apart and placing the waist bands of the trousers under tension.
45. 10. A garment hanger comprising an attaching member, a pair of spaced parallel horizontal elements secured to said attaching member, means for shifting the position of said elements laterally with respect to each other, a relatively movable member including a plate, spaced parallel horizontally disposed elements carried by said plate and telescopically engaged with said first named elements, and means for shifting the position of said second named elements laterally with respect to each other in accordance with the position of the first named shiftable elements, the telescoped elements being adapted for disposition through the belt straps at the front and back of the waist bands of trousers, and the shiftability of said telescoped elements permitting the holding of trousers having different sized waists.
50. 11. In testimony whereof I affix my signature.
MONROE S. CLAWSON.
